ATTORNEY.

UNITED STATES PATENT OFFICE.

HARRY EWART WEIGHT, OF PENARTH, WALES.

CATAMENIAL BANDAGE.

Application filed December 13, 1923. Serial No. 680,321.

To all whom it may concern:

Be it known that I, HARRY EWART WEIGHT, a subject of the King of Great Britain and Ireland, residing at 35 Plymouth Road, 5 Penarth, in the county of Glamorganshire, Wales, have invented an Improved Catamenial Bandage, of which the following is a specification.

This invention relates to an improved 10 catamenial bandage and has for one of its objects to provide a bandage giving greater comfort and having increased facilities for cleanliness as compared with known bandages, further objects being adaptability, 15 safety, efficiency and low cost.

The invention consists of a catamenial bandage comprising two endless supporting bands of elastic and nonabsorbent material of substantially circular cross section and 20 comparatively large diameter adapted to be connected to a waist belt; a container of highly flexible elastic waterproof and non-absorbent material connected to the supporting bands so as to form beads, said container 25 being formed as part of a toroidal surface and having substantially semi-circular ends the width of one end being greater than the width of the other end and the width of either end being greater than the width at 30 the middle, means of elastic and nonabsorbent character on the inner surface of the container for engaging with a pad of absorbent material, attaching means on the waist belt for engagement with the supporting bands and means adapted to allow of 35 displacement of the attaching means.

Referring to the drawings, which form part of this specification,

Figure 1 is a general view of the bandage 40 associated with a waist belt.

Figure 2 is a plan view of the container.

Figure 3 is a longitudinal section through the container taken on the line 3—3 of Figure 2.

Figure 4 is a transverse section through the container taken on the line 4—4 of Figure 2.

Figure 5 is a plan view of a template employed for the parts which when united produce a container.

The device illustrated in the drawing is comprised wholly of rubber with the exception of the waist belt which may be of any suitable material.

Referring to Figs. 2, 3, 4 and 5 of the drawing, the container *a* is formed by unit-

ing the edges *b b* of two pieces of comparatively thin unvulcanized rubber of the shape illustrated in Fig. 5 the joined pieces being vulcanized in a mould so as to result in a toroidal surface being imparted to the container *a*. In other words, the upper edge of the container is of undulatory formation, whereby the container is narrower at its middle than at its end portions. To slightly 60 stiffen the ends of the container *a* beads *c c* may be applied before vulcanization is effected.

The endless supporting bands or loops *d d* are constructed of rubber tubing and are connected to the container *a* along the edges *e e* thereof so as to form beads for retaining the absorbent material definitely in place laterally, additional strength being obtained by the employment of patches *ffff* 70 towards each end of the connection. The relatively wide end portions formed by the undulatory side edges of the container form flaps which are folded over and are secured to the endless supporting bands and the intermediate portions of the side edges of the container conform to the curvature of the supporting bands. In practice satisfactory results are obtained with india rubber tubing 75 of about $\frac{1}{4}$ of an inch in diameter.

To retain the absorbent material (not shown) in place a loop *g* is provided said loop consisting of a strip of rubber attached by its ends *h h* to the container *a*.

By the construction defined above it will readily be seen that a container adapted to properly engage with the human body is produced and that such container will not chafe the wearer or be easily displaced 90 owing to the reduced width at *a'*.

The waist belt *i* has the ordinary buckle *j* to enable its diameter to be adjusted as required; each side of the belt *i* has a plurality of button holes *k*, (in Fig. 1 of the drawing five button holes *k* are shown on each side) 100 a tab *l* having a button *m* and a button hole *n* being provided for each set of button holes *k*. The provision of the plurality of button holes *k* on each side of the belt *i* enables the tabs *l l* to be positioned relative to the hips of the wearer so that the container *a* is firmly although elastically maintained in place when the loops *d d*, which respectively pass around the thighs, are engaged by the tabs *l l* the buttons *m m* of which are passed through two of the button holes *k k* and the button holes *n n*.

Obviously, in the place of the loop or loops *g* a cap or caps may be provided.

I claim:

A catamenial bandage comprising two
• endless tubular supporting bands of elastic
and non-absorbent material of substantially
circular cross section and comparatively
large diameter adapted to be connected to
a waist belt and an elongated container of
10 elastic waterproof and non-absorbent ma-
terial having a pair of side walls of un-
dulatory formation at their upper edges

whereby the container is of reduced width
at the middle of its length and wide at its
end portions, the wide end portions forming
15 flaps which are folded over and secured
to the supporting bands and the intermediate
portions of the upper edges between the
flaps conforming to the curvature of the sup-
porting bands.

20

In testimony whereof I have signed my
name to this specification.

HARRY EWART WEIGHT.
